DESIGN FOR A HOSIERY CONTAINER OR SIMILAR ARTICLE

William C. Wagner, New York, N. Y.

Application April 29, 1941, Serial No. 100,691

Term of patent 7 years

To all whom it may concern:

Be it known that I, William C. Wagner, a citizen of the United States of America, residing in New York city, county of New York and State of New York, have invented a new, original, and ornamental Design for a Hosiery Container or Similar Article, of which the following is a specification, reference being had to the accompanying drawing, forming part thereof, wherein,

Figure 1 is a front perspective view of a hosiery container or similar article showing my new design in a closed position.

Figure 2 is an end elevational view thereof, and

Figure 3 is a view similar to Figure 1 showing my new design in an open position.

The left end of the container is the same in appearance as the right end shown, and the back is substantially the same as the front.

The characteristic feature of my design resides in the specific surface ornamentation on the container disclosed in association with the piped edges arranged on the container as shown.

I claim:

The ornamental design for a hosiery container or similar article, substantially as shown and described.

WILLIAM C. WAGNER.
